(57) **CLAIM**

The ornamental design for a hanging computer membrane as shown and described.

DESCRIPTION

FIG. 1 is a perspective view of a hanging computer membrane showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1 thereof;

FIG. 10 is a partial enlarged view of FIG. 2 thereof; and, FIG. 11 is perspective view thereof, shown in an environment of use.

The evenly-spaced broken lines shown in FIGS. 1-10 illustrate portions of the hanging computer membrane that form no part of the claimed design. The evenly-spaced broken lines illustrating the monitor in FIG. 11 are environment, while the remaining broken lines in FIG. 11 illustrate portions of the hanging computer membrane that form no part of the claimed design. The dash-dot-dash broken lines

(Continued)

encircling the enlarged views are for annotative purposes only and form no part thereof.

1 Claim, 11 Drawing Sheets
